UNITED STATES PATENT OFFICE

2,661,788

PIPE BENDING AND STRAIGHTENING
MACHINE

Paul W. Esslinger, Nampa, Idaho, assignor to
Automatic Benders, Inc., Nampa, Idaho, a corporation of Idaho

Application February 10, 1950, Serial No. 143,568

3 Claims. (Cl. 153—40)

1

This invention relates to new and useful improvements in pipe bending machines and the primary object of the present invention is to provide a machine for selectively bending and straightening electrical conduits automatically without the necessity of having to dismantle the machine each time a different diameter conduit is to be bent.

Another very important object of the present invention is to provide a pipe bending and straightening machine including a swingable form that is operated by an electric motor together with a switch for the motor that is slidably adjustable and which is actuated to a circuit open position after the member has swung a predetermined amount, so that the pipes, rods, bars or the like may be bent to various curves.

Yet another object of the present invention is the provision of a pipe bending and/or straightening machine that is so constructed as to accommodate pipes, rods, bars or the like of various diameters and which is capable of bending pipes, rods, bars or the like to various curvatures or radii.

A further object of the present invention is to provide a pipe bending and straightening machine having relatively few working parts that require very little service or repair and thereby permitting the device to be operated at a minimum expense.

A still further aim of the present invention is to provide a pipe bending and straightening machine that is extremely small and compact in structure, simple and practical in use, efficient and durable in operation, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the present invention;

Figure 2 is a plan view of Figure 1 but showing the pipe clamp moved to the lower step of the frame;

Figure 3 is a view similar to Figure 2, but showing the pipe form moved to the position it occupies after bending a pipe to a 90 degree radius, and with dotted lines showing the pipe guide and clamp moved to a position to permit removal of the pipe;

Figure 4 is a front view of Figure 3;

2

Figure 5 is a transverse vertical sectional view taken substantially on the plane of section line 5—5 of Figure 2;

Figure 6 is a transverse vertical sectional view taken substantially on the plane of section line 6—6 of Figure 2;

Figure 7 is a fragmentary perspective view of the pipe form;

Figure 8 is an enlarged detail vertical sectional view taken substantially on the plane of section line 8—8 of Figure 2; and

Figure 9 is an enlarged detail vertical sectional view taken substantially on the plane of section line 9—9 of Figure 2.

Referring now to the drawings in detail, wherein for the purpose of illustration, there is disclosed a preferred embodiment of the present invention, the numeral 10 represents a frame including a pair of stepped side portions 12 and 14, an upper rear wall 16 and a lower rear wall 18. The walls 16 and 18 join the side portions 12, 14 and are provided with elongated slots 20 and 22, the longitudinal edges of which are formed with channels or grooves 24.

The numeral 26 designates a pipe form or bending member that is formed of a plurality of steps 28, 30 and 32. The steps are quadrants of circles and include curved or arcuate outer faces 34, 36 and 38 that are formed with channels or grooves 40, 42, 44, 46, 48, and 50. The grooves vary in depth and radii to accommodate pipes, bars, rods or the like of various diameters. The faces 34, 36 and 38 are concentric with respect to each other.

The apex of the member 26, which is a common apex for all of the steps, is integrally formed with a vertical sleeve portion or trunnion 52 in which there is received a shaft 54 whose upper end supports a laterally projecting arm 56.

The upper and lower ends of the sleeve portion or trunnion 52 extends above and below the member 26 and support upper and lower bearings or collars 58 and 60 that are slidably received in the grooves 24 of the upper and lower slots 20 and 22, respectively. The collars 58 and 60 also permit rotation or swinging movement of the member 26 with respect to the frame 10.

The shaft 54 supports intermediate its ends, a hub 62 that enters a recess 64 in the sleeve portion 52. The hub 62 is secured to one end of a screw 66 whose other end enters a gear housing 68 at one end of the frame 10. The screw 66 is received in a longitudinal recess 69 in the member 26. An electric motor 70 suitably mounted beneath the frame 10 drives a pinion 72 within

the housing 68 which in turn drives a gear 74 suitably journaled in housing 68, having a threaded opening that receives the screw 66. The housing 68 includes an opening to permit the screw 66 to extend therethrough as the screw is moved longitudinally of the frame 10 to pull the sleeve portion 52 toward the side portion 14.

The step 28 of the member 26 includes a lug 76 through which bores, having radii equal to the radii of the grooves 40 and 42 extend to retain relatively small diameter pipe relative to the member 26. The step 30 also includes a lug 78 through which bores of radii equal to the radii of grooves 44 and 46 extend to retain medium size pipe relative to the member 26. The step 32 is formed with a lug 80 having a pair of bores of radii equal to the radii of the grooves 48 and 50 for receiving relatively large diameter pipe.

The upper step 32 of the side portion 14 is provided with a vertical face having a pair of horizontal grooves therein corresponding to the grooves 40 and 42; the intermediate step 84 of the side portion 14 is provided with a vertical face having a pair of horizontal grooves corresponding to the grooves 44 and 46; and, the lower step 86 of the side portion 14 is provided with a vertical face having a pair of horizontal grooves corresponding to the grooves 48 and 50.

An upper lug 88 projects laterally from the upper step of the side portion 12; an intermediate lug 90 projects laterally from the intermediate step of the side portion 12; and a lower lug 92 projects laterally from the lower step of the side portion 12.

Means is provided for clamping a pipe, rod or bar against the frame and within a selected groove in the vertical face of a selected step of the side portion 14. This means comprises an elongated substantially rectangular clamping member and guide 93 having longitudinal grooves of various sizes in its faces to accommodate pipes of various diameters. The grooves in the member 93 correspond to the grooves in the pipe form as well as the grooves in the side portion 14.

The member 93 is provided with a plurality of transverse internally threaded bores 94 in each of its ends. A pivot 96 extends through a selected one of the ears 88, 90, 92 and enters a selected one of the bores 94 in one end of the member 93 to permit horizontal swinging movement of the member 93.

The vertical surfaces of the steps 32, 84 and 86 are provided with horizontal internally threaded bores 98 for selectively registering with a bore 94 in one end of the member 93. A holding bolt 100 extends through a bore 94 in the member 93 and is threaded in a selected one of the bores 98 for clamping a pipe in a groove in the member 93 and a groove in the side portion 14.

The upper wall 16 of the frame 10 is provided with a longitudinal groove 101 having dovetail edges 102. Switch supporting arms 104 having edges complementary to the edges 102, are slidably received in the groove 101 and support push button switches 106 and 108 that are connected to the electric motor so that as the button of one of the switches is depressed, the circuit to the motor will be broken.

A spring urged locking ball 110 is carried by each of the arms 104 and yieldingly urges the dovetail edges of the arm 104 against the edges 102 to yieldingly maintain the switches 106 and 108 in a longitudinally adjusted position relative to the frame 10.

Graduations 112 in degrees are provided on

the upper face of the wall 16 adjacent the groove 101 for registering with the switches so that a selected bend can be made in a pipe.

In practical use of the present invention, the article to be bent, such as a pipe P is inserted through a lug 76, 78 or 80 conforming to its diameter and also enters a selected recess or groove in the side portion 14 to position the pipe horizontal.

Next, the member 93 is pivoted on the pin 96 against the side portion 14 and the bolt 100 is threaded in a selected one of the openings 98, it being understood that the member 93 is first applied to a selected one of the lugs 88, 90 or 92 so that the groove in the member 93 receiving the pipe will be complementary to the groove in the side portion 14 receiving the pipe.

Then, the switch 106 is moved to a selected graduation on the wall 16 depending upon the degree the pipe is to be bent, for example 90°, 60° or 45°.

As the motor 70 is started, the screw 66 and the trunnion 52 move toward the side portion 14 and the form 26 is swung clockwise about its trunnion 52 to bend the pipe since the right end portion of the pipe is clamped against the side portion 14. After the pipe has been bent to a predetermined curvature (see Figure 3) and since the trunnion 52 is moving toward the push button of the switch 106, arm 56 on the upper end of the trunnion 52 engages and depresses the button of switch 106 to stop the motor.

The bolt 100 is then backed up and the member 93 swung outwardly to permit removal of the bent pipe.

To straighten a bent pipe, for example, to straighten a pipe having a 90° bend to a 60° bend, the member 93 is swung outwardly and the bent pipe slipped through a selected one of the lugs 76, 78, 80, enters one of the grooves in the member 26 and a corresponding groove in the side portion 14.

The member 93 is then secured to the side portion 14 by the bolt 100 to clamp the bent pipe against the side portion.

The switch 108 is then moved to register with the 60° graduation on the wall 16, and the motor 70 being of the reversible type, is started to move the screw 66 to the left from its Figure 3 position and swing the member 26 counter-clockwise.

After the pipe has been bent to remove 30° of its bend, the upper end of the trunnion 52 engages and depresses the button of switch 108 and the motor becomes inoperative.

Obviously, through use of the present machine, pipes, rods, bars or the like of various diameters can be bent to any desired angle and pipes that are bent can be straightened or rebent to a desired bend.

The instant machine is capable of straightening or bending railroad track or any such bendable metallic structural members by employing matched contour shoes. The machine also functions as a vise and may be operated mechanically, as shown, or manually by a crank applied to the screw 66.

The curved shoe is approximately 93° which is necessary to overbend a pipe or the like.

Obviously, a slight marker or rise may be provided on the ends of the straight shoe, just inside of the grooves, so that an operator can replace the bend in the exact position for any further calculations. In this regard an indenture 114 will be impressed on the pipe by the rise for

registering with the rise upon replacement of the pipe.

Having described the invention, what is claimed as new is:

1. A pipe bending and straightening machine comprising a frame including a pair of spaced side members interconnected by upper and lower wall members, said upper and lower wall members having elongated apertures extending between the side members, a vertically disposed trunnion positioned between said upper and lower wall members and having its opposite end portions received in the apertures thereof, a feed worm threadedly engaged through one of said side members and extending laterally therefrom toward the other side member, said trunnion being pivotally secured to said feed worm, said one side member having a pipe receiving groove therein, an elongated bar clampingly secured at one end to said one side member and terminating at its other end adjacent said other side member, said elongated bar having a longitudinal groove therein in register with the groove in said one side member whereby a pipe is clampingly secured therebetween, a segmental pipe form rotatably mounted at its apex to said trunnion and provided with a pipe receiving groove in its arcuate marginal edge, means on said marginal edge and extending radially outwardly of said groove for engaging a pipe to be bent, said means being in abutting relation with said other end of the elongated bar when the trunnion is positioned adjacent said other side member, whereby rotation of said segmental pipe form and frictional engagement of said means with the surface of the pipe to be bent is effected when the trunnion is moved toward said one side member.

2. In a machine for bending pipe and the like, a frame, a trunnion movable longitudinally on said frame, means for moving said trunnion member longitudinally of said frame, an elongated member secured to said frame in spaced parallel relation to the path of movement of said trunnion and provided with a pipe receiving

- groove longitudinally thereof, a segmental pipe form rotatably carried at its apex by said trunnion, said segmental form having its arcuate marginal edge formed with a groove in vertical alignment with the groove in said elongated member and in opposed relation thereto, means on said marginal edge and extending radially outwardly of said groove for receiving a pipe to be bent, said last means being in abutting relation with one end of said elongated member when said trunnion is disposed at one end of the frame, whereby rotation of said segmental form and frictional engagement of said last means with the surface of a pipe to be bent is effected when the trunnion is moved toward the other end of the frame.
3. The combination of claim 2 wherein said one end of the elongated member is pivotally secured to the frame and the other end of said elongated member is detachably secured to a portion of the frame, said frame portion having a groove in register with the groove in said elongated member for receiving a pipe to be bent, said frame portion and said other end of the elongated member clampingly engaging the pipe to be bent therebetween.

PAUL W. ESSLINGER.
